UNITED STATES PATENT OFFICE.

ARNOLD EGLI, OF BERN, AND HANS GRAF, OF LAUPEN BERN, SWITZERLAND, AS-SIGNORS, BY MESNE ASSIGNMENTS, TO THE FIRM: CHOCOLAT TOBLER HOLDING CO., AKTIENGESELLSCHAFT, OF SCHAFFHAUSEN, SWITZERLAND.

SPACING DEVICE.

Application filed January 20, 1923, Serial No. 615,883, and in Germany July 27, 1922.

This invention relates to spacing devices especially to be used in type setting machines and consists especially in a device for determining the space relations of a plurality of typebars each provided with a row of characters and of spaces to be inserted between each two word units to form an adjusted line and to bring the said typebars and spaces back in front of magazines out of which they are moved.

The arrangement of the device according to the invention may be such that perforated or non-perforated plates, and if desired typebars between these plates, are firmly pressed against each other when parts of the device are moved in one direction, and when these parts are moved in the opposite direction the said plates are moved certain distances apart from each other.

The means employed according to the invention to accomplish these results may consist of pressure members, which act on external plates or the like, and of draft members provided with a number of steps or shoulders, these steps or shoulders operating, to move the plates or the like, which are provided with corresponding shoulders or notches, certain distances apart from each other. The plates which are to be pressed against each other may be threaded onto a suitable guide member or sliding support. These plates may be equipped with guiding springs between which and the neighbouring plates the typebars and spaces may be inserted which are preferably both provided with grooves or cavities into which the springs on the plates enter. An arrangement of this kind will be found advantageous for writing or typesetting machines in which typebars are employed which are normally located in magazines out of which they are moved into the printing position.

Another feature of the invention consists in associating with the outside plates of a device by which the typebars are pressed together members which are adapted to engage with the upper portions of the typebars inserted between the plates without engaging with the plates between which no typebars are inserted.

In order to keep down the size of the device a series of stepped parts may be com-

bined and displaced with respect to each other or staggered.

Other features of the invention will appear in the following description and claims.

Fig. 1 is a perspective view of two stepped moving members of a spacing device and of two plates which are to be moved a certain distance apart by the moving members.

Fig. 2 is a perspective view of modified stepping moving members with a plate held between shoulders or steps of the moving members.

Fig. 3 is a plan view of a complete spacing device consisting of a frame provided with two groups of stepped moving members, the steps of each group being adapted to act in opposite directions.

Fig. 4 is a plan view of the device in Fig. 3 but with the spacing members or moving members drawn apart.

Fig. 5 is a side view of Fig. 3 except that it is provided with special thrusting or closing members which are adapted to travel clear of the transverse intermediate plates and to engage with the objects inserted between them.

Fig. 6 is a face view of one of the transverse plates of Fig. 3 that are adapted to be pressed together.

Fig. 7 shows a perspective view of a spacing device according to the invention, parts being broken away.

Referring to the drawing *a* is a stepped moving member with steps or shoulders *b*¹, *b*², *b*³, *b*⁴, the shoulders being produced by cutting a stepped recess in the end of the plate *a*. *c* is another stepped moving member with steps or shoulders *d*¹, *d*², *d*³, these shoulders being formed on a tapering projection at the end of the plate *c* instead of in a recess at the end of the plate as in a plate *a*.

*a*¹, Fig. 2, is a moving member formed with shoulders *b*¹¹, *b*²¹, *b*³¹, *b*⁴¹ in the recessed end of the plate as in case of the member *a*, Fig. 1.

Inserted between the stepped moving members *a*, *c* are transverse plates *f*¹, *f*², these transverse plates being formed with projections or shoulders *g*¹, *g*² of different kinds. It is obvious that when the moving

members *a*, *c*, Fig. 1 are moved towards each other the transverse plates *f*¹, *f*² will be caught by the shoulders of the moving members *a*, *c* and pushed towards each other until they occupy positions in which they are clamped in between the shoulders of the moving members and are at certain distances apart. It will be obvious that additional transverse plates with suitable shaped projections could be arranged to be clamped in between the pairs of shoulders *b*², *b*² and *b*¹, *d*⁴. On the stepped moving member being drawn apart the transverse plates *f*¹, *f*² can be moved together or into contact with each other, or in other words they can then be squeezed close against each other.

In the arrangement shown in Fig. 2 the transverse plates *f*³ cooperate with the steps as *b*⁴ and *b*²¹ of the moving members *a* and *a*¹ when the latter are pressed or moved towards each other as indicated by the arrows. It will be seen that the moving members *a*, *a*¹ of Fig. 2 are in different planes and not in the same plane as in Fig. 1. It will be obvious that in addition to the plate *f*³, which is clamped in between the shoulders *b*⁴, *b*²¹, further transverse plates may be provided which could be arranged to be clamped in between the ends of the projections *b*¹¹ and the left surface of the recess *b*⁴ and between the shoulders *b*³, *b*³¹ and *b*² and *b*⁴¹ and between the ends of the projections *b*¹ and the right hand boundary of the recess *b*⁴¹. Any desired number of moving members *a*, *c*, or *a*, *a*¹ may be used. On the moving members *a*, *a*¹, Fig. 2, being pulled apart the transverse plates as *f*³ can be squeezed together.

Instead of moving members with steps formed in a recess as in the plate *a* and with cooperating steps formed on a stepped tapering projection as on the plate *c*, moving members may be employed on all of which the steps or shoulders are formed on tapering projections as in the case of the moving member or plate *c*.

In Figs. 3 and 4 a spacing device is shown which comprises two oblong frames one of which consists of the parts *h*¹, *h*², *h*³, *h*⁴, while the other consists of the parts or bars *i*¹, *i*², *i*³, *i*⁴. Fixed to, or associated with, the two longitudinal bars *h*², *h*⁴ of the one frame are two series of stepped moving members or plates, the one series *h*² being associated with the longitudinal bar *h*² and the other series *h*⁴ being associated with the longitudinal bar *h*⁴. The longitudinal bar *h*², *h*⁴ with their associated series of stepped moving members *h*¹, *h*² and the transverse bars *h*¹, *h*³ form one half of the spacing device and the longitudinal bars *i*², *i*⁴ with their associated series of stepped moving members *h*³, *h*⁴ and the transverse bars *i*¹, *i*³ form the other half of the spacing device. When the transverse bars *h*³, *i*³ are pulled

in opposite directions the two frames slide out relatively to each other into the position shown in Fig. 4 and laterally extending lugs *o* attached to the ends of the longitudinal bars *i*², *i*⁴ and *h*², *h*⁴ then carry the transverse bars *i*¹, *h*¹ towards each other and shift the transverse plates *f* close against each other. On the transverse bars *h*³, *i*³, Fig. 4, now being pushed towards each other the shoulders of the series of the stepped spacing members *h*¹, *h*² and *h*³, *h*⁴ cooperate with the transverse plates *f* in the manner explained in connection with Figs. 1 and 2 and shift them certain distances apart.

The plates *f* may be provided with slots 80 *m*, Fig. 6, through which a guiding member or table *g*, Fig. 5 is threaded, upon which the plates *f* are caused to slide. The plates *f* also have slots or perforations *m*¹, *m*² through which the longitudinal bars *h*², *h*⁴ 85 and *i*², *i*⁴ of the aforesaid frames can pass. The longitudinal bars also act as guide members.

The transverse plates may be provided with springs *n* which are adapted to enter 90 grooves formed in typebars that may be inserted between the transverse plates. The springs *n* serve as auxiliary guide members for guiding the typebars between the transverse plates. This arrangement is particularly advantageous in printing machines in which typebars are protruded from magazines into the channels between the transverse plates and then pressed close together with the said transverse plates and afterwards moved apart again into positions in which each typebar is again accurately placed before the entrance to its magazine. 100

Fig. 5 shows a side view of a device according to Fig. 3. The stepped moving members or plates are assembled in series and the transverse bars *i*¹ and *h*¹ are equipped with an adjustable pressure device or clamping device *o*¹, *o*², whose parts are adapted to travel clear of the transverse plates *f*. This clamping device is adapted to cooperate with the top portions of typebars *p* inserted between the transverse plates and which project above the top edges of these plates *f*. The typebars *p* rest upon the table or guide member *g* onto which the transverse plates *f*, provided with slots as shown in Fig. 6, are threaded. 110

Spacing devices of the kind described herein may be used for many purposes as for example in card indexes or files in which the cards are normally pressed close up against each other in order to occupy the smallest possible space, but which have to be shifted apart to enable the cards to be 120 read or taken out of the file separately. The same problem occurs in chests of drawers in which file wrappers are stored in vertical positions, and also in libraries and collections of manuscripts, etchings, samples of 125 130

cloth, paper, drawing, music, etc. The spacing device has been found particularly advantageous in book printing typewriters of the type shown in a copending application.

We claim:—

1. In a type setting machine, typebars each provided with a row of characters and adapted to form a line of types, and a series of members, adapted to move the said typebars and to be moved in one direction of movement close to each other and in the other direction predetermined distances apart from each other.
2. In a typesetting machine, the combination with relatively movable frames, of a series of relatively movable members arranged between portions of said frames which are moved towards and away from each other by the relative movements of said frames, typebars comprising rows of characters, said typebars being movable into and out of position between said members and to form a line of types, means actuated by said movable frames and movable into engagement with said movable members whereby said typebars are positioned, and means carried by said relatively movable frames and adapted to engage said typebars independently of said members for pressing said typebars together into compact order.
3. Spacing device for determining the space relations of a plurality of objects comprising a series of members adapted to receive the said objects between them and to be moved towards each other, and a stepped member for moving the members of the said series certain distances apart from each other.
4. Spacing device for determining the space relations of a plurality of objects comprising a series of members adapted to receive the said objects between them and to be moved towards each other, and a series of stepped members for moving the members of the said series certain distances apart from each other.
5. Spacing device for determining the space relations of a plurality of objects comprising a series of slotted members adapted to receive the said objects between them and to be moved towards each other, and a stepped member for moving the slotted members certain distances apart from each other, the slots in the slotted members being adapted to cooperate with the steps of the stepped members.
6. Spacing device for determining the space relations of a plurality of objects comprising a series of slotted members adapted to receive the said objects between them and to be moved towards each other, and stepped members for moving the slotted members certain distances apart from each other, the slots in the slotted members being adapted

to cooperate with the steps of the stepped members and the stepped members being adapted to be moved in opposite directions.

7. Spacing device for determining the space relations of a plurality of objects comprising a series of members adapted to receive the said objects between them and to be moved towards each other, a stepped member for moving the members of the said series certain distances apart from each other, and a guide member for guiding the said series of members.

8. Spacing device for determining the space relations of a plurality of objects comprising a series of slotted members adapted to receive the said objects between them and to be moved towards each other, stepped members for moving the slotted members certain distances apart from each other, the slots in the slotted members being adapted to cooperate with the steps of the stepped members and the stepped members being adapted to be moved in opposite directions, and a guide member for guiding the said series of slotted members.

9. In a typesetting machine, typebars each provided with a row of characters and adapted to form a line of types, and a series of members, adapted to move the said typebars and to be moved predetermined distances apart from each other.

10. In a typesetting machine, the combination with relatively movable frames, of a series of relatively movable members arranged between portions of said frames which are moved towards and away from each other by the relative movements of said frames, typebars comprising rows of characters, said typebars being movable into and out of position between said members and to form a line of types, plates connected to said movable frames for engaging and spacing said movable members whereby said typebars are located, and means carried by said relatively movable frames and adapted to engage said typebars independently of said members for pressing said typebars together into compact order.

11. In a typesetting machine, the combination with relatively movable frames, of a series of relatively movable members arranged between portions of said frames which are moved towards and away from each other by the relative movements of said frames, means operated by said movable frames for locating said members, typebars comprising rows of characters, said typebars being movable into and out of position between said members to form a line of types, and means carried by said relatively movable frames and adapted to engage said typebars independently of said members for pressing said typebars together into compact order.

12. In a typesetting machine, the combi-

nation with relatively movable frames, of a series of relatively movable members arranged between portions of said frames which are moved towards and away from each other by the relative movements of said frames, leaf-springs interposed between and tending to separate said members from each other, typebars comprising rows of characters, said typebars being movable into and out of position between said members to form a line of types and having slidable contact with said leaf-springs, and means carried by said relatively movable frames and adapted to engage said typebars independently of said members for pressing said typebars together into compact order.

13. Spacing device for determining the space relations of a plurality of objects, comprising a series of members adapted to receive the said objects between them and to be moved towards each other, means for pulling the members certain distances apart from each other, and pressure members for pressing the said objects and members together, a said pressure member being adapted to contact with a certain one of the said objects and to pass some of the said series of members.

14. In a typesetting machine, the combination with relatively moveable frames, of a series of relatively movable members arranged between portions of said frames which are moved towards and away from each other by the relative movements of said frames, typebars comprising rows of characters, said typebars being movable into and out of position between said members to form a line of types, and adjustable clamping means carried by said relatively movable frames and adapted to engage said typebars independently of said members for pressing said typebars together.

15. Spacing device for determining the space relations of a plurality of typebars, comprising a series of members adapted to receive the said typebars between them and to be moved towards each other, means for pulling the members certain distances apart from each other, and pressure members for pressing the said typebars and members together, a said pressure member being adapted to contact with a certain one of the said typebars and to pass some of the said series of members.

16. Spacing device for determining the space relations of a plurality of objects comprising a series of members adapted to move the said objects and to be moved towards each other, and a stepped member for moving the members of the said series certain distances apart from each other.

17. Spacing device for determining the space relations of a plurality of objects comprising a series of members adapted to move the said objects and to be moved towards

each other, and a series of stepped members for moving the members of the said series certain distances apart from each other.

18. Spacing device for determining the space relations of a plurality of objects comprising a series of slotted members adapted to move the said objects and to be moved towards each other, and a stepped member for moving the slotted members certain distances apart from each other, the slots in the slotted members being adapted to cooperate with the steps of the stepped members.

19. Spacing device for determining the space relations of a plurality of objects comprising a series of slotted members adapted to move the said objects and to be moved towards each other, and stepped members for moving the slotted members certain distances apart from each other, the slots in the slotted members being adapted to cooperate with the steps of the stepped members and the stepped members being adapted to be moved in opposite directions.

20. Spacing device for determining the space relations of a plurality of objects comprising a series of members adapted to move the said objects and to be moved towards each other, a stepped member for moving the members of the said series certain distances apart from each other, and a guide member for guiding the said series of members.

21. Spacing device for determining the space relations of a plurality of objects comprising a series of slotted members adapted to move the said objects and to be moved towards each other, stepped members for moving the slotted members certain distances apart from each other, the slots in the slotted members being adapted to cooperate with the steps of the stepped members, the stepped members being adapted to be moved in opposite directions, and a guide member for guiding the said series of slotted members.

22. Spacing device for determining the space relations of a plurality of objects, comprising a series of members adapted to move the said objects and to be moved towards each other, means for pulling the members certain distances apart from each other and pressure members for pressing the said objects and members together, a said pressure member being adapted to contact with a certain one of said objects and to pass some of the said series of members.

23. Spacing device for determining the space relations of a plurality of typebars, comprising a series of members adapted to move the said typebars and to be moved towards each other, means for pulling the members certain distances apart from each other, and pressure members for pressing the said typebars and members together, a said pressure member being adapted to contact with a certain one of the said typebars and to pass some of the said series of members.

24. In a typesetting machine typebars each with a row of characters, a series of members adapted to have the said typebars inserted between them and to be moved towards each other, guiding means on the said members for guiding the said inserted typebars, and means for moving the said members predetermined distances apart from each other.

5 25. In a typesetting machine typebars each with a row of characters, a series of members

adapted to have the said typebars inserted between them and to be moved towards each other, a table upon which the inserted typebars rest, and means for moving the said members predetermined distances apart from each other.

10 In testimony whereof we affix our signatures.

ARNOLD EGLI.
HANS GRAF.
